FIG. 3.

FIG. 4.

FIG. 5.

To all whom it may concern:

Be it known that I, Sid Noble, a citizen of the United States, residing at Levittown, in the county of Nassau and State of New York, have invented a new, original, and ornamental Design for a Toy Robot, of which the following is a specification, reference being had to the accompanying drawing, forming part thereof.

In the drawing:

Fig. 1 is a front elevational view of the toy robot showing my new design;

Fig. 2 is a side elevational view thereof;

Fig. 3 is a rear elevational view thereof;

Fig. 4 is a top plan view thereof; and

Fig. 5 is an elevational view of the remote control

drive member from the opposite side than that shown in Fig. 2.

I claim:

The ornamental design for a toy robot, substantially as shown.
